UNITED STATES PATENT OFFICE.

ALONZO H. BURCHARD, OF COLORADO SPRINGS, COLORADO.

RAILWAY-LANTERN ATTACHMENT.

SPECIFICATION forming part of Letters Patent No. 613,491, dated November 1, 1898.

Application filed July 9, 1898. Serial No. 685,467. (No model.)

To all whom it may concern:

Be it known that I, ALONZO H. BURCHARD, a citizen of the United States, residing at Colorado Springs, in the county of El Paso and 5 State of Colorado, have invented new and useful Improvements in Railway-Lantern Attachments, of which the following is a specification.

The invention consists in the novel construction and combination of parts hereinafter fully described and claimed.

In the accompanying drawings, Figure 1 is a longitudinal sectional view of a lantern provided with my improvements, the shade being 15 shown folded or contracted. Fig. 2 is a similar view, the shade being expanded. Fig. 3 is a longitudinal sectional view of the shade detached.

In the said drawings the reference-numeral 20 1 designates the base of the lantern, provided with a lamp 2, to which base is secured a frame consisting of the vertical bars 3, connected together by wires 4.

The numeral 5 designates the top of the 25 lantern, hinged to the upper wire 4, so as to be capable of being swung upward when desired, and is provided with a catch to hold it in place when closed.

The numeral 6 designates the chimney. 30 The parts so far described may be of any ordinary or suitable construction and form no part of the present invention.

The numeral 7 designates the shade, consisting of a coiled spring 8 of a diameter 35 somewhat larger than the chimney of the lantern, so that when expanded it will surround the latter without coming in contact therewith. The spring is provided with a cylindrical cover 9, of any suitable woven or 40 textile material of any desired color, and its upper and lower ends are secured to the top and bottom coils, respectively, of the spring. Pivoted to said bottom coil are catches 10, which when the shade is folded or contracted 45 engage with the flange 13 of the lantern-top and hold it in place. The said spring is made of a single piece of metal, the end coils being circular, while the intermediate coils are in the form of spirals and are at an angle to the 50 end coils, the latter occupying horizontal positions.

In practice, if the lantern is to be used by the trainmen of a railroad-train, the color of the shade should be red, while for others the

shades can be green or blue, according to the 55 work they are called upon to perform.

When not in use, the shade is contracted and held under the top of the lantern by the catches, so that when the top is swung outward on its pivot for removing the chimney 60 or for other purposes the shade will be carried with it and thus be held out of the way. To enable the shade and spring to fit snugly in the said top when thus contracted, they are made tapering or contracted at the upper 65 end, as shown more clearly in Fig. 3. To use the shade, the catches are disengaged, so that the spring and cover will expand so as to surround the chimney and display a light corresponding with the color of the shade. 70

All the trainmen should have their lanterns supplied with a red shade, so that they would always have means at hand for displaying a danger-signal without necessitating the expense of an extra lantern. It is also the purpose to have the trainmen supplied with a 75 number of these shades of different colors, which when not in use are contracted, and the catches secured to the lower coil of the spring are engaged with the upper coil, so as 80 to hold the spring in its contracted position, so that it will take up but little room.

Having thus fully described my invention, what I claim is—

In a lantern, the combination with the frame 85 and the pivoted top, of the coiled spring made from a single piece of metal, the intermediate coils of which are in the form of spirals while the end coils are circular in form and at an angle to the said intermediate coils so 90 as to occupy a horizontal position, the spring-catches pivoted to the lower coil of the spring, and adapted to engage with the lantern-top, and the shade of textile or woven material surrounding said spring and having its edges 95 secured to said top and bottom coils and said catches when the spring is removed from the lantern adapted to be engaged with the upper coil of the spring, substantially as described. 100

In testimony whereof I have hereunto set my hand in presence of two subscribing witnesses.

ALONZO H. BURCHARD.
